UNITED STATES PATENT OFFICE

134,514

DESIGN FOR A COOKIE JAR

Rudy V. Ganz, Zanesville, Ohio, assignor to Shawnee Pottery Co., Zanesville, Ohio

Application October 9, 1942, Serial No. 108,487

Term of patent 14 years

To all whom it may concern:

Be it known that I, Rudy V. Ganz, a citizen of the United States, residing at Zanesville, in the county of Muskingum and State of Ohio, have invented a new, original, and ornamental Design for a Cookie Jar, of which the following is a specification, reference being had to the accompanying drawing, forming part thereof.

I claim:

The ornamental design for a cookie jar, as shown.

RUDY V. GANZ.
